US00D335465S

United States Patent [19]

Garrison, III

[11] Patent Number: Des. 335,465

[45] Date of Patent: ** May 11, 1993

[54] AIR GAUGE TIRE VALVE

679516 7/1929 France 73/146.2

[76] Inventor: Edmund E. Garrison, III, 909
Johnson Rd., Maryville, Tenn. 37201

Primary Examiner—Alan P. Douglas
Assistant Examiner—Antoine D. Davis
Attorney, Agent, or Firm—Leon Gilden

[**] Term: 14 Years

[57] CLAIM

[21] Appl. No.: 567,655

The ornamental design for an air gauge tire valve, as
shown and described.

[22] Filed: Aug. 15, 1990

DESCRIPTION

[52] U.S. Cl. D10/86

FIG. 1 is a front elevational view of the air gauge tire
valve showing my new design;

[58] Field of Search D10/86; D8/387; 73/146,
73/146.2, 146.3, 146.4, 146.5, 146.6, 146.8

FIG. 2 is a rear elevational view thereof;
